UNITED STATES PATENT OFFICE.

EDWARD M. HEWLETT, OF SCHENECTADY, NEW YORK, ASSIGNOR TO GENERAL ELECTRIC COMPANY, A CORPORATION OF NEW YORK.

ELECTRIC HEATER.

No. 882,564.

Specification of Letters Patent. Patented March 24, 1908.

Application filed August 3, 1907. Serial No. 386,959.

To all whom it may concern:

Be it known that I, EDWARD M. HEWLETT, a citizen of the United States, residing at Schenectady, county of Schenectady, State 5 of New York, have invented certain new and useful Improvements in Electric Heaters, of which the following is a specification.

This invention relates to resistance devices for electric circuits and has for its object the 10 provision of a device of this character which is of a simple and durable construction and at the same time thoroughly reliable and efficient.

My invention relates more specifically to 15 resistance devices for use in electric heaters or the like, although certain phases of my invention are capable of a wider application.

One of the objects of my invention is to 20 provide an electric atmospheric heater or radiator, which is intended to be operated at a relatively low heat and can be brought up to its working temperature in a comparatively short time.

25 Another object of my invention is to produce an electrical heater which may be constructed at a very low cost, the parts being almost entirely of sheet metal and the resistance elements themselves being punchings 30 which may be easily assembled and durably constructed.

Other objects of my invention will appear 35 in the course of the following specification in which I have set forth my invention in a specific form for purposes of illustration.

In the drawings in which I have shown my invention embodied in a concrete form, Figure 1 is a sectional elevation of one form of my invention; Fig. 2 is a transverse section 40 of the same; Fig. 3 is a perspective view of the resistance unit; Fig. 4 is an elevation of a modified form of my invention; Fig. 5 is a side elevation of the same; Fig. 6 is a view of the disk as punched; and Fig. 7 is a view of 45 the completed disk.

Referring to the drawings, 10 is a metallic casing shown circular in form and preferably closed at the top by a plate 11 and provided with perforations 12. The bottom of the 50 casing likewise has a plate in which are openings 13 to permit a circulation of air through the casing. Mounted in the bottom of this casing is a supporting rod 14 secured to the bottom plate and extending about half way up the casing. Upon this rod and insulated

therefrom are mounted a series of parallel resistance disks 15. These disks may be circular in form and are preferably punched or stamped from resistance metal such as sheet iron or the like. The form of these disks 60 when first punched is shown in Fig. 6, being a grid-shaped structure with a central opening 16. The form of the punching is such that it constitutes a strip extending back and forth from the central opening 16 in radial lines so 65 that the path through the metal will be in a zigzag form running in and out from the center. In order to stiffen the plate, the portions 17 and 18 are bent at right angles to the plane of the disk along the dotted lines shown 70 in Fig. 6 so as to form stiffening webs although this may not always be found necessary. The disks are assembled on the rod 14 which passes through the opening 16, insulating washers 19 being interposed between 75 the disks and an insulating sleeve 20 between the rod and the disks. The disks are then tightened down and the rod is held in place by means of the nuts 21. The arrangement 80 whereby the connections are made between the successive disks is shown in Fig. 3 in which it is seen that the edges of the disks are split at 22, and at the adjacent ends are bent, one up and one down, and fastened together, as shown, so as to form a continuous path 85 throughout the disks.

In the form shown in Fig. 1 the terminals 23 are secured to the bottom plate and from there connected to the disks.

In Figs. 4 and 5 I have shown a slightly 90 modified form in which the casing 24 is rectangular in section and is curved at the upper end 25 in the shape of a hood so as to project the air through the openings or perforations 26. In this form two resistance units 27 95 and 28 are employed and hooks 29 are arranged to permit of suspending the heater on the wall.

It will be seen that I have produced a very 100 simple and efficient heater which will come up to its working temperature in a comparatively short time. It requires very little labor in its construction and will stand rough usage without injury.

Various modifications both as to the heater 105 itself and the form of the resistance unit will suggest themselves to those skilled in the art, all of which I consider is within the spirit of my invention in so far as they fall within the scope of the claims annexed hereto. 110

What I claim as new and desire to secure by Letters Patent of the United States, is,—

- 5 1. A resistance unit comprising a support, a plurality of disks mounted thereon, each consisting of a resistance strip extending back and forth from the support, and connections between said disks whereby a continuous path for the current is established throughout the said disks.
- 10 2. A resistance unit comprising a plurality of disks each consisting of a resistance strip extending back and forth from a common center, a central support therefor, and connections whereby a continuous path for the current is established throughout the said disks.
- 15 3. A resistance unit comprising a plurality of disks each consisting of a resistance strip extending back and forth from a common center and provided with stiffening webs, a central support therefor, and connections whereby a continuous path for the current is established throughout the said disks.
- 20 4. An electric heater comprising a casing having a plurality of grid-shaped resistance disks mounted in parallel arrangement thereon, and connections whereby a continuous path for the current is established throughout the said disks.
- 25 5. An electric heater comprising a casing, a support therein, a plurality of disks each consisting of a resistance strip mounted upon said support and extending back and forth therefrom, and connections whereby a con-
- tinuous path for the current is established 35 throughout the said disks.
6. An electric heater comprising a closed casing, a resistance unit arranged to occupy a portion of said closure, said unit consisting of a plurality of spaced grid-shaped disks, 40 and connections whereby a continuous path for the current is established throughout the said disks.
7. An electric heater comprising a casing, a support therein, a plurality of disks mounted in parallel arrangement upon said support, each consisting of a resistance strip extending towards and from said support in radial lines, and connections whereby a continuous path for the current is established throughout 45 the said disks.
8. An electric heater comprising a casing, a supporting rod therein, a plurality of parallel disks spaced from each other and mounted on but insulated from the said rod, said 50 disks each consisting of a resistance strip extending back and forth from the rod as a center and provided with stiffening webs, and connections whereby a continuous path for the current is established throughout the 55 said disks.
9. An electric heater comprising a casing, a support therein, a plurality of disks each consisting of a resistance strip mounted upon said support and extending back and forth therefrom, and connections whereby a continuous path for the current is established throughout the 60 said disks.

In witness whereof, I have hereunto set my hand this 26th day of July, 1907.

EDWARD M. HEWLETT.
